GUN HAVING SLIDING AND INTER-
CHANGEABLE BARRELKarl Kehne, Berlin-Tegel, Germany; vested in
the Alien Property CustodianApplication February 20, 1939, Serial No. 257,508
In Germany October 7, 1935

2 Claims. (Cl. 42—75)

In guns having exchangeable barrels, barrel-securing devices are known which automatically prevent a shot being fired when the barrel is not properly positioned in the gun or when the barrel is not properly locked. In the known arrangements a safety member, influenced by the coupling of the breech casing to the barrel, immediately locks the breech mechanism when the barrel is imperfectly coupled with the gun, so that it is impossible for the gun to be loaded unless the barrel has been coupled satisfactorily.

Furthermore, it is known in connection with guns having a reciprocating and exchangeable barrel to couple the barrel and a locking sleeve in such a manner that a guide member mounted in the gun casing engages, in the coupling position, in longitudinal grooves in the barrel and thus axially locates the barrel.

The invention is concerned with the problem of providing an improved safety-device of the last named type in such a manner that the manipulation of the safety-device itself and also of the barrel is simplified by means which control the assembling and dismounting movement. According to the invention, with this object in view at the rear end of the known longitudinal groove there is connected a guide groove which affords positive guidance to the barrel over the entire course of its assembling and dismounting movement, and in which the guide member can enter after having been removed from the longitudinal groove. By giving the guide groove a suitable shape, according to the present invention an improvement in such barrel safety-devices is obtained, whereby the gun is prevented from being cocked if the barrel has not been completely coupled, and the barrel is prevented from being clamped while it is imperfectly coupled, as is possible with the known safety devices. This result is obtained by the guide groove first running transversely to the longitudinal groove on the barrel for a distance depending on the length of the barrel locking teeth, and then parallel to the said longitudinal groove as far as the rear end of the barrel.

The adjustment of the guide for the barrel to its normal position at the conclusion of the mounting of the barrel, calls attention from the outset to the proper or improper performance of the locking of the barrel. If the guide for the barrel does not engage in its normal or locking position—owing to a faulty barrel coupling or accidental omission owing to lack of attention, the guide will then coat with the trans-

verse groove of the barrel to prevent the barrel from being moved back to load the gun, which thus compels the gunner to bring the barrel fixing into a satisfactory coupled state before the gun can be fired.

5 The drawing illustrates a typical embodiment of the invention, namely as applied to a large-calibre machine gun having a reciprocating barrel, a locked breech, and a barrel fixing of the bayonet catch type.

Fig. 1 is a longitudinal section through the middle part of the gun.

Fig. 2 is a cross section through the barrel at II—II, Fig. 1 but with the barrel guide shoe turned into alignment with the transverse groove.

15 Fig. 2a is a side view of a detail view of the guide.

Fig. 3 is a view, partly in section, of the breech end of the barrel.

20 The barrel *a* of the gun is adapted to be removed from the breech casing *b*, in the example illustrated, from the front in known manner, but the invention is applicable to other removable barrel constructions. Patent No. 2,014,184, issued September 10, 1935, shows one form of removable barrel and Patent No. 1,994,489, issued March 19, 1935, shows another structure.

25 The breech block is locked to the breech casing *b* in a manner which is usual in guns of the kind in which the breech block *d* does not open in order to eject a fired cartridge or for loading, and also just after a change of barrel has been made, until it has covered a certain distance in the backward direction, in the condition in which it is closed and locked with the breech casing *b* and the barrel *a*.

30 In order that it may be fixed in position the barrel *a* has, at its rear end, two uniform rows of bayonet catches or teeth *a*₁ distributed over its periphery, which locking teeth *a*₁ when the barrel *a* has been inserted in the proper manner, engage over their entire width with counter-teeth *b*₁ on the breech casing *b*, this casing being so arranged as closely to embrace the barrel at its front portion over a considerable length.

35 In the coupled position shown in Fig. 1 the barrel *a* is secured by a locking pin *e* which is mounted in the gun casing *c*, and, under the influence of a spring *e*₁, is thrust inwards so as to locate a guide projection *e*₂ in a slide groove *a*₂ and thus axially position the barrel. The projection *e*₂ forms a guide shoe the width of which corresponds to the width of the guide groove *a*₂, but having a greater length, the shoe being formed

in the example shown, by flattening two sides of a cylindrical head.

On the knob *f* of the pin *e* which projects from the gun casing *c*, there are provided projections *f*₁ which engage in corresponding notches in the gun casing *c* and thus secure the shoe *e*₂ in the position necessary to enable it axially to guide the barrel. By raising the pin *e* against the pressure of the spring *e*₁ until the projections *f*₁ disengage from the notches in the casing, the knob *f* with the pin *e* can be turned, and after turning through 90° the pin *e* is held in a raised position which brings the foot of the shoe *e*₂ in alignment with a transverse groove *g* in the barrel casing serving to mount and dismount the barrel.

For this purpose, as may be seen from Figs. 2 and 3, there is provided at the junction of the longitudinal groove *a*₂ and the peripheral or transverse groove *g* a cylindrical recess *a*₃ the diameter of which corresponds to the maximum dimension of the shoe *e*₂, and the depth of which is such that the walls of the recess extend to the base of the groove *a*₂ which runs longitudinally on the barrel casing. The arrangement of the recess *a*₃ and the projections *f*₁ necessitates the raising and the turning of the shoe *e*₂ into the position necessary to enable the barrel to be changed and in this position the base of the shoe *e*₂ is held level with the bottom of the transverse groove *g*, but is not high enough to be flush with the peripheral surface of the barrel. The sliding shoe *e*₂, when in the raised and turned position, thereby forms, in the assembly and dismounting of the barrel, an abutment that prevents the barrel from being drawn back when the coupling of the barrel has not been properly carried out and secured and thus precludes the possibility of the gun being loaded in such case. Into the transverse groove *g*, there opens another longitudinal groove *g*₁ which extends to the rear end of the barrel. The length of the transverse groove *g* depends on the peripheral length of the locking teeth *a*₁ on the barrel, while the width of the groove *g*₁ corresponds to the greater dimension of the slide shoe *e*₂.

After the pin *e* has been raised and turned through 90°, the slide shoe stands in the position shown in Figs. 2 and 3, i. e. with its narrow side disposed to the groove *g* so that an unbolting, pivotal movement of the barrel *a* can take place. The disengagement of the barrel teeth *a*₁ from the counterteeth *b*₁ in the breech casing is completed as soon as the longitudinal groove *g*₁ of the barrel, which extends rearwards at right angles to the groove *g*, comes opposite the shoe *e*₂. Any further pivotal movement of the barrel in the unlocking direction is thus prevented. Now, the barrel can be drawn forward axially and withdrawn from the breech casing *b* and, therefore, from the gun.

A new barrel can be inserted only when it occupies an angular position which is determined by the guiding of the slide shoe *e*₂ in the longitudinal groove *g*₁, when, the breech casing *b* being in its forward end position in the gun, the insertion of the barrel automatically brings the teeth *a*₁ opposite the gaps of the locking teeth *b*₁ of the breech casing *b*. The limitation of the inward movement of the barrel, to the position in which the teeth of the barrel *a* and of the breech casing *b*

are correctly relatively disposed to enable the barrel and breech casing to be locked together, which is effected by the striking of the shoe *e*₂ against the front wall of the transverse groove *g*, and its accurate centering in the junction of the grooves *g* and *a*₂, permitting turning movement as necessary for the locking operation. When the barrel attains the completely coupled position, this position is indicated by the abutment of the shoe *e*₂ against the walls of the circular recess *a*₃. If now the shoe *e*₂ is turned back through 90° until the projections *f*₁ engage in the grooves in the casing, the barrel *a* is fully secured and the gun is again ready for loading.

15 In the present case the locking teeth on the barrel *a* and the breech casing *b* have no screw pitch, so that when the barrel is inserted its linear inward movement is limited by the rear end of the barrel striking against the shoulder *b*₂ of the breech casing *b*.

If the locking teeth of the barrel *a* and the breech casing *b* have a coarse screw pitch, for instance in order to loosen the cartridge case during the unbolting operation, then, naturally, 25 the transverse groove *g* must also be given a corresponding inclination. In this case the barrel would be prevented from being inserted further than the proper locking position merely by the co-action of the shoe *e*₂ and the groove *g*.

30 I claim:

1. An automatic firearm of the reciprocating exchangeable barrel type comprising a firearm casing, a breech casing slidable therein, a removable barrel, bayonet joint coupling means on said

35 barrel and breech casing whereby said barrel is removably mounted, and a guide member in said firearm casing settable into normal and unlock- 40 ing positions projecting different amounts from said casing, said guide member having a cylindri- 45 cal guide shoe with opposed parallel flats, and said barrel having therein a guide groove of a width corresponding to the flattened portion of the guide shoe, said groove extending longitudinally forwardly of the barrel from near its rear 50 end for a length corresponding to the travel of the barrel in firing and being engaged by said guide shoe only when the guide member is set in normal position, a transverse groove joined at one end to 55 said longitudinal guide groove, said transverse groove being of length corresponding to the turning movement to operate the bayonet joint, and an additional longitudinal groove joined to the other end of said transverse groove and extending through to the rear end of said barrel, said trans- 60 verse and additional longitudinal grooves being of a depth corresponding to the projection of the guide shoe when set in unlocking position and of widths for cooperation with said guide shoe to guide the barrel in coupling and uncoupling said bayonet joint means.

2. A firearm according to claim 1, in which the longitudinal guide groove and the transverse groove are joined by a cylindrical recess of a diameter corresponding to the diameter of the cylindrical part of the guide shoe and having its walls extending to the bottom of the longitudinal groove.

KARL KEHNE.
